UNITED STATES PATENT OFFICE

SEVERIN HALVORSEN, OF CHICAGO, ILLINOIS, ASSIGNOR TO THE NEWSPAPER STUFFING MACHINE COMPANY, OF SEATTLE, WASHINGTON, A CORPORATION OF WASHINGTON

DELIVERY MECHANISM FOR NEWSPAPER STUFFING OR SIMILAR MACHINES

Application filed May 20, 1922. Serial No. 562,463.

My invention relates to delivery mechanisms for newspaper stuffing or similar machines, particularly mechanisms in which newspapers or other articles are fed to the bottom of a pile so that they may be removed manually or otherwise from the top of the pile.

One of the objects of the invention is to provide a simple and practical delivery mechanism of the class specified.

Another object of the invention is to secure quickness and effectiveness of operation.

Another object of the invention is to assure proper piling of the papers or articles and to prevent interference of the papers one with another and also to prevent the papers from being jammed or creased or improperly folded.

In the accompanying drawings Fig. 1 is a plan view of a delivery mechanism embodying my present invention;

Fig. 2 is an end elevation of the same;

Figs. 3 and 4 are vertical sections taken on lines 3—3 and 4—4 respectively, in Fig. 1;

Figs. 5 and 6 are cross sectional views of details of construction;

Fig. 7 is a cross section taken on line 7—7 in Fig. 1;

Fig. 8 is a front elevation of the mechanism;

Figs. 9 to 16, inclusive, are views of details of construction.

Referring to the drawings, I show a delivery mechanism for piling and delivering newspapers, so that the newspapers may be introduced or inserted into the pile at the bottom thereof and continually pushed upwardly so that they may be taken off from the top. This mechanism is particularly adapted for use in connection with newspaper stuffing machines, in which newspapers comprising a plurality of sections are put together or stuffed, as it is called, by the insertion or introduction of one or more sections or parts into another section or part which is called the "cover" section. It will be apparent that the mechanism can be used for other purposes.

Referring first to Figs. 1, 3 and 8, I show a body frame having an upright 1 which may be suitably mounted on a floor or otherwise;

also a hopper member 2 in front of the body member 1. The member 2 has a hopper 3 into which the articles to be piled and delivered are fed. In the stuffing machine the completed newspapers are preferably fed to the delivery mechanism in an upright condition, the inner or insert sections being introduced or stuffed into the cover section most conveniently in such vertical condition. In Figs. 1 and 7 a completed newspaper A is shown being fed into the hopper 3 in a substantially vertical position. The movement of the finished newspaper A is accomplished by the newspaper stuffing machine which is understood to be associated with and located immediately adjoining the delivery mechanism set forth herein. A roller 5 is shown for feeding the newspaper to the hopper, such roller being part of the newspaper stuffing machine and being mounted on a shaft 6 supported in bearings 7—7 and driven by gear wheels 8, 9 and 10, Fig. 8, which are in turn driven by a sprocket chain 11.

The newspaper A coming into the hopper 3, as shown in Fig. 7, is engaged and swung upwardly so that it assumes a horizontal position at the top of the chamber 3, as shown in Fig. 3, in which position it is supported by abutments 12 and 13. The newspapers are thus fed one after the other into the chamber 3 and then engaged and swung upwardly so as to form a pile, as shown in Figs. 3 and 8, the papers being fed one after the other to the bottom of the pile and the whole pile being elevated little by little and the upper end of the same being free so that papers may be taken from the pile by hand or otherwise in any desired number.

The engaging and swinging mechanism involves a swinging plate 15 having one end provided with a plurality of hooks 16, the plate 15 being adapted to act against the side of the newspaper and arranged to swing so as to move and lift the paper from a vertical to a horizontal position. The hooks 16 engage the lower or folded edge of the paper and hold it in proper position during the upward swinging movement, as shown in Fig. 17, the member 2 having a curved surface 18 corresponding substantially with the curve made

by the folded edge of the newspaper as it is swung upwardly.

The actuating plate 15 with its hooked member 16 is operated by suitable mechanism 5 to give it the requisite swinging movement. This mechanism comprises a swinging arm 19 pivotally connected at 20 to the back of the plate 15. The arm 19 is pivotally mounted on shaft 21 which latter is supported in bearings on the main frame 1. Said arm 19 is actuated by a reciprocating link 22 pivoted to the arm at 23, the link 22 having bifurcated end portions 24 to straddle the arm 19 and engage the pin 23. There are two side arms 15 19^a similar to arm 19. The link 22 is connected at 25 to a rotary wheel 26 so that the rotation of the wheel 26 will actuate the link 22 to swing the arm 19 backwardly and forwardly to lift a paper A into horizontal position and then to retract and come into position to engage another paper in vertical position and swing the same into horizontal position. The wheel 26 is mounted on a shaft 27 mounted in bearings 28-28 (Fig. 1).

The abutment 12 is mounted so that it can be moved into and out of the path of travel of the newspaper A, so that said papers may be pushed up beyond said abutment and then rest on the same. As a simple arrangement 30 said abutment 12 is formed as part of a swinging member 30 pivoted at 31 and subject to a spring 32 tending to swing said member inwardly. Said member 30 is provided with an inclined surface 33 against which the 35 newspapers or other articles will strike and an abutment or stop 34 is arranged opposite the lower end of the member 33 to engage the lower end of the member 30 and prevent the same swinging unduly inward. Thus when 40 a newspaper is swung up by the swinging member or platen 15, the outer or folded end of said newspaper will strike against and slide along the inclined surface 33 thereby pushing member 30 outwardly against the action of spring 32 and permitting the newspaper being swung upwardly to pass above abutment 12 formed on member 30. After 45 passing above said abutment 12, member 30 will swing back inwardly, thereby permitting 50 abutment 12 to come into position underneath the outer or folded edge of said paper which thereupon rests upon said abutment so that the latter serves to support the pile of papers. After the member 30 swings back inwardly to 55 place the abutment 12 in supporting position platen 15 is retracted so as to move into its downward position to act upon another paper.

Abutment 13 is held in position by the frame of the machine, as for example, by being bolted by means of bolt 35 to downwardly projecting lug or bracket 36. Said abutment 13 has an inclined surface 37 and a finger 38 extending downwardly and then slightly inwardly and positioned and arranged so as to 60 cooperate with the upper end of the platen 15,

Thus the end of the platen 15 slides along the finger 38 and inclined surface 37 as said platen is swung upwardly to raise a newspaper, the result of which is that the newspaper will be moved so that its inner or unfolded end will come into position upon the top of abutment 13 when platen 15 is in substantially horizontal position, as shown in Fig. 3.

In order to lift the pile sufficiently to permit each additional paper to come into position above abutment 13, means are provided for lifting the pile just prior to the insertion of each paper above said abutment. As one arrangement for accomplishing this, I show a lifting device 40 having three lifting members or fingers 41-41, said member 40 being mounted on a rock shaft 42, which is in turn supported by bearings 43 and is given a certain amount of up and down movement, so that the members 41 may push against the lowermost paper in the pile and lift the same to permit the introduction of another paper, and may also be moved so as to withdraw from underneath the pile after the additional paper has been inserted, and permit the pile to rest on said additional paper. In Fig. 2 one of the fingers 41 is shown pushed upwardly against the lowermost one of a pile of papers to lift the same and allow the insertion of another paper below the pile, and in Fig. 3 this additional paper is shown inserted in position below the pile and the arm 41 is about withdrawn so as to permit the upper papers to settle and rest upon the new papers just inserted.

As an arrangement for actuating this member 40 in this way, the bearings 43 for the shaft 42 are mounted on the arm 44 of a bell crank 45 mounted on a sleeve 45^a which carries a floating shaft 46 and another arm 47, both 47 and 45 being pinned to 45^a. The arm 47 is actuated by connections with the rotary shaft 27. These connections comprise a yoke or cross head 48 mounted to slide on a bearing block 49 on shaft 27, said yoke being pivotally connected by a pin 50 with the lower end of arm 47. Yoke or cross head 48 carries two rollers 51 and 52, whereof the roller 51 is adapted to cooperate with cam 53 on shaft 27 and roller 52 is adapted to cooperate with cam 54 on said shaft. By this arrangement arm 47 is given a positive reciprocating motion by said cams so that the arm 44 will be raised and lowered to position lifting member 40 as required. The end of arm 44 is provided with rollers 44^a (Figs. 7 and 11), along which the platen 15 will roll as it swings upwardly. Spring 15^a is connected to platen 15 and arm 19, tending to hold platen 15 in a back position against rolls 44^a.

In order to rock the member 40 so as to move its fingers 41 in the proper manner, a reciprocating link 57 is provided and connected by pin 58 with a rocker arm 59. A link 57 is pivotally connected at 60 with a

wheel 60^a (Fig. 2) mounted on shaft 46 which carries gear 61 meshing with gear 62, the latter being on a shaft 63 which is understood to be the main drive shaft of the machine. This gear 62 also meshes with a gear 64 on shaft 27 so as to drive the latter and the mechanism operated thereby. By such arrangement gear 63 reciprocates link 57 and thereby causes the projecting arms or fingers 41 to swing about the shaft 42 as required, while at the same time this shaft 52 is raised and lowered by rocking movement of bell crank arm 44, as previously described. Movement is imparted to member 40 by rocking of shaft 42 by means of ratchet mechanism comprising a spring controlled dog 65 cooperating with a toothed wheel 66 on the shaft 42, so that shaft 40 is rotated continuously in the direction indicated by arrow 19 in Fig. 2. Dog 65 is supported and mounted by pivot 68 on arm 59 which in turn is supported on arm 57. An annular member 69 is pivotally connected at 70 to link 71 mounted on shaft 72, so that up and down movement of shaft 42 may be taken care of at the same time that rocker arm 59 is being actuated by link 57. A ring 73 of friction material is provided within bracket ring 69 cooperating with friction members 74 to insure proper action of the ratchet mechanism. Shaft 42 is held in position for operation of arms 41 by recesses 42^a in collar 42^b on shaft 42 and roller 42^c on arm 42^d, (Fig. 9). Spring 42^e attached to arm 42^d holds roller 42^c in said recesses 42^a.

As a preferred arrangement provision is made for indicating the number of papers stacked in the pile. To such end provision is made so that certain papers may be projected beyond the others, the projecting papers being a predetermined number of papers apart. For example, as shown in Fig. 8, papers A' are projected beyond the others. The papers A' may be every fifth, tenth or other paper as desired. As arranged they are twelve papers apart so that each one indicates a dozen papers in the pile.

To such end a platen or abutment member 75 is arranged at one end of the chamber or space 3 (Fig. 2), so that the papers fed into the space 3 will strike against said member 75, and provision is made for moving this member 75 outwardly at a predetermined time to permit one newspaper to be advanced further than the others, whereby this one newspaper will become a paper A' which projects beyond the others.

As an arrangement for automatically moving the member 75 outwardly at predetermined intervals and returning it for intervening periods of time, said plate 75 is shown mounted on a swinging arm 76 which latter is mounted on a vertical rock shaft 77 supported in bearings 78. Said shaft 77 also carries an arm 79 having its outer end provided

with a roller 80 which latter travels on a circular race 81, which race, however, has a recess 82 into which the roller 80 may move. A spring 83, (Fig. 5) normally pulls upon arm 79 and when roller 80 and recess 82 come together, said roller will fall into said recess and thereby permit spring 83 to pull arm 79 inwardly and thereby swing the arm 76 outwardly and withdraw plate 75 a small distance, as indicated in dotted lines in Fig. 5. Therefore a paper fed into the hopper 83 at a time when member 75 is withdrawn will be displaced relatively to the position of the other papers as previously described. The annular race 81 is formed on a rotary wheel 85 which is mounted on shaft 86 which latter is provided with ratchet mechanism adapted to turn shaft 86 in a step by step movement which is arranged to bring the recess 82 into position to cooperate with roller 80 at predetermined intervals of time. The ratchet mechanism shown comprises a dog 87 carried on an arm 88 pivotally connected with the lower end of a link 89 (Fig. 4), which link 89 is connected with a cross head 90 mounted on cam 91 carried on shaft 46. Thus rotation of the shaft 46 will cause reciprocation of link 89 and actuation of ratchet mechanism to intermittently turn wheel 85 and thereby, through recess 82 and wheel 80 allow spring 83 to swing arm 76 and retract platen 75 and thereby allow one paper to be advanced beyond the others. In the mechanism shown this one paper will be each twelfth paper, whereby when said paper is swung up to take its position in the stack or pile it will project beyond the other papers, as shown in Fig. 8.

From the foregoing it will be seen that the newspapers or other articles may be fed forward one after another to the hopper 3 in a substantially vertical position and will be engaged one after another and swung upwardly into substantially horizontal position and pushed against the bottom of a pile of papers or other articles so that each paper or article will take its position at the bottom of the pile, and the papers or articles already there will be continually pushed upwardly. Papers or articles may be taken from the top of the pile in any amount or quantity desired, and continuously or at intervals as desired, so that the stack or pile may be removed as convenient. This action takes place continuously and automatically and rapidly and accurately. It will be understood as previously mentioned that articles other than newspapers may be fed, piled and stacked or delivered by this invention and also that the invention may be used other than with a newspaper stuffing machine.

It will be understood that changes and modifications may be made without departing from the spirit of the invention.

What I claim is:

1. A machine of the class specified comprising means for acting upon an article in a substantially vertical position and swinging it up to substantially horizontal position and placing it at the bottom of a stack or pile of similar articles arranged one upon another. 5
2. A machine of the class specified comprising means for acting upon an article in a substantially vertical position and swinging it up to substantially horizontal position and placing it at the bottom of a stack or pile of similar articles arranged one upon another, and means for engaging and holding the lowermost of said articles so as to support the stack or pile. 10
3. A machine of the class specified comprising a hopper into which articles may be fed in substantially vertical position, a swinging platen adapted to engage said articles and swing them from such vertical position into substantially a horizontal position and to place them at the bottom of a stack or pile of similar articles arranged one upon another and means for lifting said stack or pile so as to permit the insertion of the lowermost article into the position previously occupied by the lowermost article of the stack or pile. 15
4. A machine of the class specified comprising a hopper into which an article may be fed in substantially vertical position, means for feeding an article into the hopper in vertical position and means for swinging said article into substantially horizontal position to place it at the bottom of a stack or pile of articles arranged one above another. 20
5. A machine of the class specified comprising a hopper into which an article may be fed in substantially vertical position and means for swinging said article into substantially horizontal position to place it at the bottom of a stack or pile of articles arranged one above another, said means comprising a swinging platen mounted to swing from substantially vertical to substantially horizontal position, a swinging arm pivotally connected with said platen and means for actuating said swinging arm. 25
6. A machine of the class specified comprising a hopper into which an article may be fed in substantially vertical position and means for swinging said article into substantially horizontal position to place it at the bottom of a stack or pile of articles arranged one above another, said means comprising a swinging platen mounted to swing from substantially vertical to substantially horizontal position, a swinging arm pivotally connected with said platen and means for actuating said swinging arm, said actuating means comprising a reciprocating link pivotally connected to said arm and a rotary member to which said link is pivotally connected. 30
- 65 7. A machine of the class specified comprising a hopper into which an article may be fed in substantially vertical position and means for swinging said article into substantially horizontal position to place it at the bottom of a stack or pile of articles arranged one above another, and hook members at the outer ends of said platen for engaging the outer edge of said article. 70
8. A machine of the class specified comprising a hopper into which an article may be fed in substantially vertical position and means for swinging said article into substantially horizontal position to place it at the bottom of a stack or pile of articles arranged one above another, and hook members at the outer ends of said platen for engaging the outer edge of said article, and spring means tending to hold said platen in retracted position. 75
9. A machine of the class specified comprising a hopper to receive articles in substantially vertical position, a swinging member to engage said articles and swing them to a horizontal position, means for actuating said swinging member and means for supporting a stack or pile of articles substantially at or below the upper limit of movement of said swinging member. 80
10. A machine of the class specified comprising a hopper to receive articles in substantially vertical position, a swinging member to engage said articles and swing them to a horizontal position, means for actuating said swinging member and means for supporting a stack or pile of articles substantially at or below the upper limit of movement of said swinging member, said supporting means comprising abutments on opposite sides of the upper portion of the hopper. 85
11. A machine of the class specified comprising a hopper to receive articles in substantially vertical position, a swinging member to engage said articles and swing them to a horizontal position, means for actuating said swinging member and means for supporting a stack or pile of articles substantially at or below the upper limit of movement of said swinging member, said supporting means comprising abutments on opposite sides of the upper portion of the hopper, one 90
- 115 of said abutments being movable into and out of position in the hopper and being spring controlled to hold it normally in supporting position in the hopper. 105
12. A machine of the class specified comprising a hopper to receive articles in substantially vertical position, a swinging member to engage said articles and swing them to a horizontal position, means for actuating said swinging member, means for supporting a stack or pile of articles substantially at or below the upper limit of movement of said swinging member, and means for pushing the stack or pile upwardly to make room for another article at the bottom of the same. 110
- 125 130

13. A machine of the class specified comprising a hopper to receive articles in substantially vertical position, a swinging member to engage said articles and swing them to a horizontal position, means for actuating said swinging member, means for supporting a stack or pile of articles substantially at or below the upper limit of movement of said swinging member, and means for pushing the stack or pile upwardly to make room for another article at the bottom of the same, said means comprising a lifting member mounted for vertical adjustment and adapted to strike against the lowermost article of the pile and to lift the same.

14. A machine of the class specified comprising a hopper to receive articles in substantially vertical position, a swinging member to engage said articles and swing them to a horizontal position, means for actuating said swinging member, means for supporting a stack or pile of articles substantially at or below the upper limit of movement of said swinging member, and means for pushing the stack or pile upwardly to make room for another article at the bottom of the same, said means comprising a lifting member mounted for vertical adjustment and adapted to strike against the lowermost article of the pile and to lift the same, said lifting member being movable so as to permit its movement out of the way of the last addition to the pile after it has lifted said pile.

15. A machine of the class specified comprising a hopper to receive articles in substantially vertical position, a swinging member to engage said articles and swing them to a horizontal position, means for actuating said swinging member, means for supporting a stack or pile of articles substantially at or below the upper limit of movement of said swinging member, and means for pushing the stack or pile upwardly to make room for another article at the bottom of the same, said means comprising a lifting member mounted for vertical adjustment and adapted to strike against the lowermost article of the pile and to lift the same, said lifting member being movable so as to permit its movement out of the way of the last addition to the pile after it has lifted said pile, said member comprising a rotary device having a plurality of curved arms, the backs of which are adapted to strike against the bottom of the pile and lift the same and the ends of which are adapted to be moved out of position below the pile by the rotation of said member.

16. A machine of the class specified comprising a hopper to receive articles in substantially vertical position, a swinging member to engage said articles and swing them to a horizontal position, means for actuating said swinging member and means for supporting a stack or pile of articles substantially at or below the upper limit of movement of said

swinging member, and means for pushing the stack or pile upwardly to make room for another article at the bottom of the same, said last mentioned means comprising a rotary device having a plurality of radially extending curved arms adapted to strike against and lift the pile of articles and then to move out of the way of an article to be placed at the bottom of the same, a swinging arm on which said rotary device is mounted and means for swinging said arm so as to raise and lower said rotary device.

17. A machine of the class specified comprising a hopper to receive articles in substantially vertical position, a swinging member to engage said articles and swing them to a horizontal position, means for actuating said swinging member and means for supporting a stack or pile of articles substantially at or below the upper limit of movement of said swinging member, and means for pushing the stack or pile upwardly to make room for another article at the bottom of the same, said last mentioned means comprising a rotary device having a plurality of radially extending curved arms adapted to strike against and lift the pile of articles and then to move out of the way of an article to be placed at the bottom of the same, a swinging arm on which said rotary device is mounted and means for swinging said arm so as to raise and lower said rotary device, said swinging means comprising another arm connected with said first mentioned arm and a rotary shaft provided with cams and connections for swinging said arms by said cams.

18. A machine of the class specified comprising a hopper to receive articles in substantially vertical position, a swinging member to engage said articles and swing them to a horizontal position, means for actuating said swinging member and means for supporting a stack or pile of articles substantially at or below the upper limit of movement of said swinging member, and means for pushing the stack or pile upwardly to make room for another article at the bottom of the same, said last mentioned means comprising a rotary device having a plurality of radially extending curved arms adapted to strike against and lift the pile of articles and then to move out of the way of an article to be placed at the bottom of the same, a swinging arm on which said rotary device is mounted, means for swinging said arm so as to raise and lower said rotary device, and means for rotating said rotary member comprising a ratchet mechanism and means for driving the same.

19. A machine of the class specified comprising a hopper to receive articles in substantially vertical position, a swinging member to engage said articles and swing them to a horizontal position, means for actuating said swinging member and means for

supporting a stack or pile of articles substantially at or below the upper limit of movement of said swinging member, and means for pushing the stack or pile upwardly to make room for another article at the bottom of the same, said last mentioned means comprising a rotary device having a plurality of radially extending curved arms adapted to strike against and lift the pile of articles and then to move out of the way of an article to be placed at the bottom of the same, a swinging arm on which said rotary device is mounted, means for swinging said arm so as to raise and lower said rotary device, and means for rotating said rotary member comprising a ratchet mechanism and means for driving the same, said driving means being connected with means for swinging said arm.

20. A machine of the class specified comprising a hopper to receive articles in substantially vertical position, a swinging member to engage said articles and swing them to a horizontal position, means for actuating said swinging member and means for supporting a stack or pile of articles substantially at or below the upper limit of movement of said swinging member, and means for pushing the stack or pile upwardly to make room for another article at the bottom of the same, said last mentioned means comprising a rotary device having a plurality of radially extending curved arms adapted to strike against and lift the pile of articles and then to move out of the way of an article to be placed at the bottom of the same, a swinging arm on which said rotary device is mounted, and means for swinging said arm so as to raise and lower said rotary device, said swinging means comprising another arm connected with said first mentioned arm and a rotary shaft provided with cams and connections for swinging said arm by said cams, and means for rotating said rotary member comprising ratchet mechanism adapted to rotate the same, said ratchet mechanism being driven by a rotary member gear connected with the rotary shaft on which said cams are mounted.

21. A machine of the class specified having means for indicating the number of articles piled or delivered, said means comprising mechanism by which predetermined separated articles may be projected beyond the intervening articles, said means comprising a platen for adjusting the edges of said articles and means for holding said platen in normal position for a given number of articles and for retracting the same for other predetermined articles, said mechanism comprising a swinging arm carrying said platen and a cam device controlling said arm, said cam device comprising a rotary member having an annular race provided with a recess and a supplemental arm cooperating with said first mentioned arm and provided with a roller for travelling on said race and enter-

ing said recess, and means for rotating said rotary member.

22. A machine of the class specified having means for indicating the number of articles piled or delivered, said means comprising mechanism by which predetermined separated articles may be projected beyond the intervening articles, said means comprising a platen for adjusting the edges of said articles and means for holding said platen in normal position for a given number of articles and for retracting the same for other predetermined articles, said mechanism comprising a swinging arm carrying said platen and a cam device controlling said arm, said cam device comprising a rotary member having an annular race provided with a recess and a supplemental arm cooperating with said first mentioned arm and provided with a roller for travelling on said race and entering said recess and means for rotating said rotary member, said rotating means comprising ratchet mechanism connected with and operated by a rotary member.

23. A machine of the class specified comprising a swinging member arranged to engage an article in a substantially vertical position and to swing it up to substantially horizontal position and place it at the bottom of a stack or pile of similar articles arranged one on top of another.

24. A machine of the class specified comprising a swinging member arranged to engage an article in a substantially vertical position and to swing it up to substantially horizontal position and place it at the bottom of a stack or pile of similar articles arranged one on top of another, means for swinging said member and means for engaging and holding the lowermost of said articles so as to support the stack or pile.

25. The combination with means for holding a pile of articles of means for lifting one side of the pile to make room for another article at the bottom, said means comprising a swinging member adapted to act upwardly upon the lowermost article of the pile and then to move sideways beyond the wide edge of said lowermost article to permit the additional article to come into position below said lowermost article.

26. The combination with means for holding a pile of articles of means for lifting one side of the pile to make room for another article at the bottom, said means comprising a swinging member adapted to act upwardly upon the lowermost article of the pile and then to move sideways beyond the wide edge of said lowermost article to permit the additional article to come into position below said lowermost article and means for introducing such additional article at the bottom on the pile.

27. The combination with means for holding a pile of articles, of a lifting device ar-

5 ranged to act upon the lowermost article of the pile and lifting one side of the same so as to make room at the bottom for another article, and a swinging member arranged to move an additional article into position at the bottom of the pile while the pile is in a lifted position.

10 28. The combination with means for holding a pile of articles of means for lifting one side of the pile to make room at the bottom for another article, said lifting means comprising a swinging arm arranged to act upwardly on the pile and then move outwardly from same and means for moving an additional article into the space formed by the 15 action of said swinging arm.

20 29. The combination with means for holding a pile of articles of means for lifting one side of the pile to make room at the bottom for another article, an abutment at one side of the holding means, said lifting means being adapted to lift the lowermost article of the pile sufficiently above said abutment to permit the introduction of another article above 25 the abutment and below the pile, and means for introducing such additional article into the space so formed.

30 30. The combination with means for holding a pile of articles of means for lifting one side of the pile to make room at the bottom for another article, an abutment at one side of the holding means, said lifting means being adapted to lift the lowermost article of the pile sufficiently above said abutment to permit 35 the introduction of another article above the abutment and below the pile, and means for introducing such additional article into the space so formed, said lifting means comprising a swinging arm adapted to act upwardly upon the lowermost article of the pile and to move to one side of the pile and the means for introducing the additional article comprising a swinging platen adapted to engage and move said article.

40 31. A delivery mechanism having a lifting device comprising a swinging arm adapted to act upwardly upon the pile and then to swing laterally to one side of the pile.

45 32. In a delivery mechanism a lifting device comprising a swinging arm adapted to act upwardly on the pile and having a recessed or chambered portion into which an additional article may be moved when said arm is acting upon the lowermost article of the pile.

50 33. In a delivery mechanism, a lifting device comprising a swinging arm having a convex portion to act upon the lowermost article of the pile and also having a concave portion in which the edge of an additional article may be arranged while the convex portion of the arm is acting upon the lowermost article of the pile.

55 34. In a delivery mechanism, a pile moving device comprising a swinging arm hav-

ing a convex portion for acting on the pile and also having a concave portion for the edge of an additional article and means for moving said swinging arm toward and away from the pile to make it effective in lifting same.

35. In a delivery mechanism, a curved swinging arm, having its convex portion toward the pile in order to lift the same and also having its concave portion adapted to receive the edge portion of the additional article inserted at the bottom of the pile.

70 36. In a delivery mechanism, a curved swinging arm, having its convex portion toward the pile in order to lift the same and also having its concave portion adapted to receive the edge portion of the additional article inserted at the bottom of the pile and means for moving said swinging arm toward and away from the pile.

75 37. In a delivery mechanism, a curved swinging arm, having its convex portion toward the pile in order to lift the same and also having its concave portion adapted to receive the edge portion of the additional article inserted at the bottom of the pile and means for moving said swinging arm toward and away from the pile, and an abutment on which one edge of the pile normally rests, said swinging arm being adapted to lift the lowermost article of the pile above said abutment to form space between the same and the lowermost article of the pile for the additional article.

80 38. In a delivery mechanism a pile lifting swinging arm provided with a curved portion, the convex part of which is adapted to act on the pile and the concave part of which is adapted to receive the edge of an article, said arm being also provided with a surface adapted to receive the edge portion of the additional article as the same is being inserted at the bottom of the pile.

85 39. In a delivery mechanism a pile lifting swinging arm provided with a curved portion, the convex part of which is adapted to act on the pile and the concave part of which is adapted to receive the edge of an article, said arm being also provided with a surface adapted to receive the edge portion of the additional article as the same is being inserted at the bottom of the pile in combination with a lifting member adapted to lift the additional article and move the same into position at the bottom of the pile.

90 40. In a delivery mechanism, a rotary lifting device provided with a plurality of arms each of which is adapted to act upon the pile so as to lift the same.

95 41. In a delivery mechanism, a rotary member provided with a plurality of curved arms for acting on the endmost member of a pile of articles.

100 42. In a delivery mechanism, a rotary member provided with a plurality of curved

arms for acting on the endmost member of a pile of articles in combination with means for moving said rotary member toward and away from the pile.

43. In a delivery mechanism, the combination of a rotary member having a plurality of arms adapted to act upon a pile of articles and a swinging member for introducing an additional article at the bottom of the pile, said swinging member being arranged to cooperate with the arms of said rotary member.

44. In a delivery mechanism, the combination of a rotary member having a plurality of arms adapted to act upon a pile of articles and a swinging member for introducing an additional article at the bottom of the pile, said swinging member being arranged to cooperate with the arms of said rotary member in combination with means for moving said rotary member toward and away from the pile.

45. In a delivery mechanism, a swinging member moving the articles to be delivered, in combination with hook devices adapted to engage the articles while being moved by said member.

46. In a delivery mechanism, a swinging member moving the articles to be delivered, in combination with hook devices adapted to engage the articles while being moved by said member.

47. In a delivery mechanism the combination of a rotary member provided with a plurality of arms and a swinging platen arrangement to cooperate with said arms and a hopper having a curved surface along which the platen moves the articles to be delivered.

48. In a delivery mechanism, the combination of a rotary member having a plurality of curved arms and also having surfaces between said arms for accommodating edge portions of the articles to be delivered, and a swinging platen arranged to engage and move the articles and cooperating with the rotary member so that the edge portions of the articles rest on said surfaces while the articles are being moved by the platen.

49. The combination of a hopper and means for feeding articles to the hopper in one plane and means for moving said articles in the hopper at an angle to the plane in which they were introduced, so that the articles will be delivered from the hopper in a different plane.

50. In a delivery mechanism, the combination of means for feeding an article to the hopper in one plane and a swinging platen adapted to engage the article and swing it to a plane at an angle to the plane of insertion.

In witness whereof, I hereunto subscribe my name this 28th day of April, A. D. 1922.

SEVERIN HALVORSEN
